(57) **CLAIM**

The ornamental design for a liquid spray emitter, as shown and described.

DESCRIPTION

This application claims priority to U.S. patent application Ser. No. 11/464,377, filed on Aug. 14, 2006 and entitled “Lawn Mower Cleaning Device”.

FIG. 1 is a perspective view of the design;

FIG. 2 is an end elevational view of the design;

FIG. 3 is a side elevational view of the design;

FIG. 4 is a top plan view of the design; and,

FIG. 5 is a bottom plan view of the design.
